DOOR LATCH

Fred J. Gefri, Irvington, N. J.

Application January 13, 1941, Serial No. 374,286

2 Claims. (Cl. 292—359)

The present invention relates to door latches and more particularly to latches for motor vehicle doors.

An important object of the invention resides in the provision of a door latch associated with the inner door handle and embodying means for latching the door on the interior of the vehicle to prevent accidental or unauthorized opening of the door.

Another object of the invention resides in the provision of a latch device attached to the inner door handle which will automatically latch the door from the interior of the vehicle to prevent accidental opening thereof.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a fragmentary longitudinal vertical sectional view of a portion of a vehicle door with the improved latch associated therewith.

Figure 2 is a vertical sectional view taken substantially on line 2—2 of Figure 1.

Figure 3 is a detail sectional view taken substantially on line 3—3 of Figure 1.

Figure 4 is a view similar to Figure 3 with the inner door handle depressed for releasing the latch.

Figure 5 is a view similar to Figure 4 with the mechanism raised for latching the door.

Referring to the drawing for a more detailed description thereof, a motor vehicle door is generally designated by the reference numeral 6, the interior of which is provided with the usual upholstery 6, the outer portion of the door being designated by the reference numeral 1. The improved latch comprises an outer cylinder 8 fixedly held within the door and which extends through the upholstery 6 into the interior of the door as is clearly shown in Figures 1 and 2 of the drawing. Vehicle doors are ordinarily provided with a central brace 9 and the cylinder 8 is attached thereto by means of a pair of angular brackets 10, said brackets fastened to the brace 9 by bolts or the like 11, the projecting end of the cylinder 8 having the brackets 10 welded or otherwise secured thereto.

An inner cylinder 12 is mounted within the cylinder 8 for rotary and axial movement with

relation thereto. A stub shaft 13 that is substantially square-shaped in cross section, projects from one end of the cylinder 12 to which the inner door handle 14 is attached by means of a pin or the like 15. As is to be understood, the cylinder 8 is provided with a cap 16 suitably secured to the end of the cylinder and the shaft 13 extends through an opening 17 formed in said cap. For presenting a finished appearance to the handle and the interior of the car, there is provided an ornamental annular member 18 which surrounds the inner end of the handle 14 and is suitably held in engagement with the upholstery 6.

The other end of the cylinder 12 is provided with a shaft 19 that is also substantially square-shaped in cross section, said shaft extending through an opening 20 formed in the central brace 9. The shaft 19 also extends through an arm 21 which arm is connected at its lower end to a lever 22 that connects with the conventional door locking mechanism, not shown. A plate 23 formed with flanges 24 is suitably secured to the central brace 9 and forms a cover for the arm 21. The shaft 19 extends through an opening 25 formed in the plate 23, the outer end of the arm supporting a washer 26. A tension spring 27 is disposed between the washer 26 and the face of the plate 23, said spring adapted to return the shaft 19 and cylinder 12 to normal position upon the release of pressure on the handle 14 as will hereinafter appear.

The end of the cylinder 8 that is in engagement with the central brace 9 is closed as indicated at 28 and said closed end is formed with an arcuate-shaped slot 29, through which a pin 30 is adapted to project. The pin 30 is carried by the inner cylinder 12 and when in engagement with the slot 29 will prevent actuation of the door locking mechanism.

The pin 30 by reason of its engagement in the slot 29 prevents the handle 14 from being moved downwardly to operate the arm 21 and lever 22 which would normally release the door locking mechanism. However, the handle 14 can be moved upwardly for latching the door from the interior of the car in the conventional manner. In order to open the door from the interior of the car, the handle 14 must be pulled inwardly which moves the cylinder 12 and its shafts 13 and 19 and at the same time the pin 30 will be retracted from the slot 29. With the handle pulled inwardly and by depressing downwardly thereon, the arm 21 and lever 22 will be actuated in the normal manner to retract the door lock-

ing mechanism. As the handle 14 is pulled inwardly tension will be created on the spring 21 and upon the release of pressure on said handle, the spring 21 will return the cylinder 12 and its pin 30 to normal position, which position includes engagement of the pin 30 in the slot 29 to again automatically lock the door. In Figure 4 of the drawing, it will be observed that the pin 30 has been retracted from the slot 29 and that the handle 14 has been pressed downwardly for releasing the door locking mechanism. In Figure 5 of the drawing, the pin 30 is shown in the uppermost portion of the slot 29 with the handle 14 moved upwardly, which position said handle would assume when locking the door in the conventional manner. In Figure 2 the inner cylinder 12 is shown in the position it would assume with the handle 14 being pulled inwardly for retracting the pin 30 from the slot 29.

Thus it will be seen that an improved latching means has been incorporated within the conventional mechanism of a motor vehicle door for automatically locking the door, thereby precluding accidental opening thereof. In parking a vehicle, certain locks require that the inside handle be moved upwardly and the present improvement has been designed for use therewith. In all instances, however, it is necessary to depress the inner handle in order to release the lock for opening the door from the interior of the car and in accordance with the present invention, said handle must be pulled inwardly, or toward the operator of the handle, which will permit disengagement of the pin 30 from the slot 29 whereupon downward movement of the handle 14 will actuate the conventional locking mechanism.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the

invention nor exceed the scope thereof as expressed in the appended claims.

What is claimed is:

1. In a door latch of the character described, 5 a cylindrical casing adapted to be mounted in transversely fixed position in a door, the said casing having an inwardly directed annular flange at the inner end provided with an arcuate slot, a cylindrical plunger mounted to turn and to slide axially in the casing, a shaft section secured to and extending axially outward of the plunger and casing, an operating handle fastened to the outer end of the said shaft section, an inner shaft section secured to and extending axially from the plunger and through the inner end of the casing, a pin secured eccentrically to the inner end of the plunger and projecting axially inward thereof and releasably engageable with the arcuate slot, latch operating mechanism connected with the inner shaft section, and spring means disposed to yieldingly slide the plunger to an inward position and cause the pin to engage the arcuate slot.

2. In a door latch of the character described, 25 a cylindrical casing adapted to be mounted in a transverse position in a door, the inner end of the said casing having an inwardly directed flange provided with an arcuate slot, a cylindrical plunger axially slidable and rotatable in the casing, a pin secured in an eccentric position to the inner end of the said plunger and projecting axially inward thereof, an outer shaft section secured to the outer end of the plunger and extending axially therefrom through the outer end of the casing, an operating handle fastened to the outer end of the said shaft section, an inner shaft section secured to the inner end of the plunger and extending axially therefrom through the inner end of the casing, a latch operating arm connected with the intermediate portion of the inner shaft section and operable thereby, and a spring sleeved about the said inner shaft section operative to yieldingly thrust the said section and the plunger to its extreme inner position to cause the said pin to engage the arcuate slot whereby to releasably hold the latch operating arm in latch closing position.

FRED J. GEFRI.
